US0D1065449S

(12) **United States Design Patent** (10) **Patent No.:** **US D1,065,449 S**
(45) **Date of Patent:** **** Mar. 4, 2025**

(54) **FAUCET**

(71) Applicant: **Guangzhou Weishui Jiaju Co., Ltd.**,
Guangzhou (CN)

(72) Inventor: **Min He**, Guangzhou (CN)

(73) Assignee: **Guangzhou Weishui Jiaju Co., Ltd.**,
Guangzhou (CN)

(**) Term: **15 Years**

(21) Appl. No.: **29/803,101**

(22) Filed: **Aug. 10, 2021**

(51) LOC (15) Cl. **23-01**

(52) U.S. Cl.

USPC **D23/238**

(57) **CLAIM**

The ornamental design for a faucet as shown and described.

DESCRIPTION

FIG. 1 is a perspective view of a faucet of the present invention.

FIG. 2 is a front view thereof.

FIG. 3 is a rear view thereof.

FIG. 4 is a left view thereof.

FIG. 5 is a right view thereof.

FIG. 6 is a top view thereof; and,

FIG. 7 is a bottom view thereof.

The broken lines are included for the purpose of illustrating portions of the article and forms no part of the claimed design.

1 Claim, 7 Drawing Sheets
